UNITED STATES PATENT OFFICE.

DAVID BROWN, OF ELDORADO, ILLINOIS.

RAILROAD-CROSSING SIGNAL.

Application filed December 31, 1925. Serial No. 78,686.

This invention relates to certain new and useful improvements in railroad crossing signals, and has more particular reference to mechanical signals of the above kind.

5 The primary object of the invention is to provide a railroad crossing signal which is extremely simple and durable in construction as well as efficient in operation.

A further object of the invention is to 10 provide a signal of the above kind embodying signal arms adapted to be brought to an operative position by the train approaching a crossing whereby the arms will point toward the train and thereby indicate the 15 direction from which the train approaches the crossing.

A further object is to provide a railroad crossing signal particularly useful for installation upon railway tracks upon which 20 traffic is adapted to move in both directions.

A still further object of the invention is to provide improved means for actuating the signal members including ramps depressible by the car wheels.

25 With the above general objects in view, and others that will become apparent as the nature of the invention is better understood, the same consists in the novel form, combination and arrangement of parts hereinafter more fully described, shown in the accompanying drawings and claimed.

In the drawings, wherein like reference characters indicate corresponding parts throughout the several views.

35 Figure 1 is a top plan view, partly broken away, illustrating a railroad crossing signal apparatus constructed in accordance with the present invention and with certain of the signal arms in lowered operative position;

40 Figure 2 is a side elevational view of the device shown in Figure 1;

Figure 3 is a central longitudinal sectional view taken substantially upon line 3—3 of Figure 1;

45 Figure 4 is a transverse section taken substantially upon line 4—4 of Figure 1;

Figure 5 is a transverse section taken upon line 5—5 of Figure 1;

50 Figure 6 is an enlarged fragmentary detail view partly in top plan and partly in

horizontal section to reveal details of the signal arm actuating means;

Figure 7 is a fragmentary side elevational view of one of the railway track rails modified for associating a ramp therewith in accordance with the present invention;

Figure 8 is a fragmentary longitudinal section taken substantially upon line 8—8 of Figure 1 and drawn on a larger scale;

Figure 9 is a horizontal section taken on line 9—9 of Figure 8;

Figure 10 is a vertical section taken upon line 10—10 of Figure 9;

Figure 11 is an enlarged perspective view of one of the drums which are operatively connected to the signal arms and actuated by the ramps, and

Figure 12 is a view similar to Figure 4 illustrating a modification of my invention.

Referring more in detail to the drawings, 5 and 6 indicate the parallel rails of a railway track which is intersected by a road or highway as at 7. Associated with each rail of the track are two ramps 8 and 8^a of similar form, the ramp 8 being located at

75 one side of and adjacent to the road crossing 7, and the other ramp 8^a being located at the other side of and a considerable distance from the crossing 7. Each ramp is slidably keyed upon an end portion of a

80 transverse rock shaft 9 which is suitably journaled in the webs of the rails 5 and 6. The end portion of each rock shaft 9 which carries its associated ramp projects outwardly beyond the latter where it is also

85 supported by and journaled in an upstanding arm 10 formed by bending the end of a tie plate 11 upwardly as more clearly shown in Figure 5, the tie plate 11 being suitably fastened upon a tie 12 by means of spikes

90 or the like as at 13. Encircling the end portion of each shaft 9 between the associated arm 10 and the adjacent end of the ramp carried by said shaft 9 is a helical compression spring 14 which may be en-

95 cased and by means of which the ramp is yieldingly held against the adjacent outer side of the adjacent rail of the track. This rail is preferably modified by cutting away

100 a portion of the tread or ball thereof as

clearly indicated at 15 so that the major portion of the adjacent ramp normally occupies a position within the cutaway portion 15 so that the wheels of the cars may ride thereon. Each ramp is thus mounted parallel with the adjacent rail and normally disposed to project from its associated shaft 9 upwardly above the top of the rail so that the ramp will be depressed when the wheels of the cars ride onto the same from a certain direction. The construction thus far described is identical at both sides of the track, except that the ramps at one side of the track or associated with one rail project in an opposite direction from that in which the other ramps associated with the other rail project. It is thus apparent that when a train approaches the crossing 7 travelling from right to left in Figure 1, the wheels of the cars constituting the train will ride onto the ramps associated with the rail 5 so as to depress the same. However, the free ends of the ramps are directed outwardly laterally and preferably rounded or beveled as generally indicated at 16 so that the wheels of a car travelling toward the left of Figure 1 will not cause the ramps associated with the rail 6 to be depressed. In other words, the wheels of these cars will pass between the ramps and the rail 6 with which such ramps are associated so as to force the latter ramps outwardly laterally away from the rail 6 as allowed by the springs 14 and the slidable keying of the ramps on their associated rock shafts. In a like manner, the ramps associated with the rail 5 will remain inoperative while the ramps associated with the rail 6 are depressed, should the train approaching the crossing be travelling in a direction from left to right of Figure 1.

Mounted at the outer side of the free end of each of the ramps for rotation upon a vertical axis is a drum 17 provided with a relatively deep peripheral cam groove 18 which is engaged by a ball or roller 19 suitably provided upon the outer end of a laterally and outwardly projecting rigid arm or pin 20 carried by the free end of the adjacent ramp. The cam groove 18 is disposed obliquely of the drum as clearly shown in Figure 7 and it is thus apparent that when any ramp is depressed, the associated drum 17 is caused to partially rotate by reason of the engagement of the ball or roller 19 in the groove 18 of said drum. Each drum 17 is preferably mounted upon a vertical pintle or axle 21 which is rigidly mounted in a vertical position by passing through the center of a base plate 22 fixed upon the top of a foundation 23 that is preferably constructed of concrete and embedded in the ground as illustrated in Figure 2. The base plate 22 preferably forms the bottom of a suitable casing 24

removably disposed to surround and enclose the drum 17, and for permitting ease of rotation of the drum, suitable anti-friction rollers 25 may be provided between the lower end of the drum and the upper surface of the base plate 22 as clearly illustrated in Figure 10. The casing 24 thus effectively protects the parts therein from the elements, and said casing is preferably provided with a vertical elongated slot 26 in which the pin or arm 20 is movable for permitting the vertical movement of the associated ramp.

A pair of signal arm supporting stands or posts is mounted at each side of the crossing 7, one post or stand of each pair being located at each side of the track. A transverse rock shaft 28 is journaled in and projects through each pair of posts or stands 27 and the track rails 5 and 6, and secured upon the ends of this rock shaft at the outer sides of the associated posts or stands 27 are pulleys 29 and 30. The upper end of each post 27 is preferably bifurcated as at 31 for reception of the end portion of a signal arm 32 fixed upon a horizontal shaft 33 that is journaled through the bifurcated portion of the post to extend transversely of the track and which has a pulley 34 fixed upon its outer projecting end. The pulley 34 associated with each post 27 is vertically aligned with the pulley 29 or 30 disposed directly therebelow for a purpose which will presently become apparent.

The drum 17 associated with each ramp 8 has an end of a flexible member or cable 35 attached to the periphery thereof, and this cable extends from such drum to and around the far side of the pulley 29 located at the same side of the track. This cable then passes upwardly around the near side of the pulley 34 disposed directly above said pulley 29 and then downwardly around the near side of such pulley 29, from which it extends under the crossing and has its other end attached to the periphery of the drum 17 associated with the ramp 8^a positioned at the same side of the track. Each pulley 30 is operatively connected with the pulley 34 disposed thereabove by means of a crossed belt 36 of endless form, and it is thus apparent that the ramps associated with one rail are operatively connected to the pair of signal arms 32 at one side of the crossing while the ramps associated with the other rail are operatively associated with the signal arms at the other side of the crossing. It will also be noted that the signal arms 32 are adapted to normally occupy a vertical upwardly projecting inoperative position and are adapted to be swung downwardly toward the crossing to a horizontal operative position. It will also be noted that each ramp 8^a is operatively associated with the pair of signal arms which are dis-

posed at the opposite side of the road crossing from that at which such ramp 8^a is disposed so that when the ramp 8^a at either side of the crossing is depressed by the 5 wheels of a train approaching the crossing from the side of the latter at which the ramp 8^a is disposed, the signal arms which are lowered will point toward the approaching train and thereby indicate the direction 10 from which the train is approaching.

The signal arms 32 are mounted at an elevation so as not to interfere with the passage of vehicles therebeneath, and suitable means for attracting attention to the arms may be 15 provided such as flags, 37 which are shown associated with some of the arms or signal lamps 38 shown associated with others of the signal arms.

The grooves 18 of the drum 17 are made 20 quite deep so that the balls or rollers 19 are normally positioned only part way into said grooves for allowing lateral movement of the ramps bodily away from the rails when forced outwardly by the car wheels against 25 the action of the springs 14 as outlined above.

Interposed in the end portions of the cables 35 are helical tension springs 39 which render the cables elastic to absorb 30 shock due to sudden riding of the car wheels onto the ramps, and for avoiding jerks and jars so that the various parts will operate smoothly and will not become readily damaged in operation. While the springs 39 are 35 illustrated as exposed, the same may be positioned so as to be enclosed in guide tubes 40 carried by the drum casings 24, in which case the guides 40 may be enlarged sufficiently to encase the springs. The guides 40 40 are in communication with openings in the casings 24 through which the cables project for attachment to the drums, and such cables may also pass through suitable conduits if found necessary. Any suitable or desired 45 provision may be made for lubrication and protection of various parts without departing from the spirit and scope of the invention.

Assuming that the signal arms are in their 50 normal vertical position and that a train is approaching the crossing from the right of Figure 1 with all of the ramps projecting above the rails of the tracks, the wheels of the cars will ride onto the ramp 8^a associated with the rail 5 and cause the same to be depressed. This depression of the ramp 8^a associated with rail 5 will cause rotation of the associated drum 17 so as to exert a pull upon the cable 35 beside the rail 5 by reason 55 of winding of said cable upon the drum. This causes rotation of the pulley 29 adjacent the rail 5 in a counter-clockwise direction and a similar rotation of shaft 28 and pulley 30 associated with said pulley 29. 60 By reason of the passage of the specified

cable about the pulley 34 above said pulley 29 in the manner hereinbefore described, and by reason of the use of the crossed belt 36 between the pulley 30 and 34 operatively associated with the shaft 28 on which said pulley 29 is fixed, the signal arms 32 at the far side of the crossing will be swung downwardly to an operative horizontal position as shown in Figures 1 to 3 inclusive. These arms will therefore point toward the train 75 to indicate the direction from which it is approaching, and at the same time the operative cable will be unwound from the drum associated with the ramp 8 at the same side of the track whereby said ramp 8 is raised. 80 The wheels of the cars will pass between the ramps associated with rail 6 and said rail 6 so as to force the latter ramps outwardly against the action of the associated springs 14, and by reason thereof the signal arms 85 located at the right hand side of the crossing will not be disturbed. As the ramps 8^a are disposed at a considerable distance from the crossing, the signal will be lowered in sufficient time to give warning before reaching 90 the crossing. As soon as the last car passes the crossing, the ramp 8^a will be allowed to rise and will be caused to do so by depression of the ramp 8 associated with the rail 5, which also causes the signal arms which have 95 been lowered to again raise to normal inoperative position. The springs 39 permit the signal arms to remain lowered even though the ramp 8 be so depressed after the ramp 8^a has been depressed. In other words, 100 assuming that the wheels have depressed the ramp 8^a for lowering a pair of signal arms, and that such wheels then pass on and depress the ramp 8 while other wheels still ride onto the ramp 8^a, the springs 39 will be stretched or placed under tension for permitting the signal arms to remain lowered. Thus, depression of the ramp 8 will effect 105 raising of the signal arms only when the wheels do not depress the cooperating ramp 8^a as is the case after a train has completely 110 passed the crossing. When a train approaches the crossing from the left of Figure 1, substantially the same operation takes place except that the ramps associated with rail 5 are forced away from such rail so that the signal arms at the left hand side of the crossing are not disturbed, while the ramp 8^a associated with rail 6 is depressed for 115 lowering the signal arms at the right hand side of the crossing and the ramp 8 associated with rail 6 is depressed for effecting return of the right hand signal arms to their normal inoperative or raised position after the train passes the crossing. It is noted 120 that the pulleys 29, 30 and 34 may be enclosed as indicated by dotted lines at —C—, and the signal arms 32 are counter-balanced so as to be easily swung. It is further noted 125 that with all of the signal arms 32 raised, 130

ramps 8^a will project above the tread surfaces of the rails and the highest parts of the ramps 8 will be level with such surfaces. Slack in the cables 35 may be taken up by turnbuckles —T—.

As shown in Figure 12, the stands or posts 27 may be placed farther from the rails and the pulleys 29, 30 and 34 located at the inner sides of said stands or posts.

10 What I claim as new is:—

1. In a railroad crossing signal, a movable signaling element mounted adjacent the crossing, vertically swinging depressible ramps associated with the railroad track and respectively disposed at opposite sides of the crossing adjacent to and remote from the latter, a drum mounted for rotation upon a vertical axis adjacent the free end of each ramp, operative connections between the free end of each ramp and the adjacent drum whereby said drum is caused to partially rotate in one direction upon depression of the ramp and in the other direction upon raising of said ramp, and operative connections between the drums and the signal elements including a flexible member having its ends anchored to and adapted to be wound upon said drums.

2. In a railroad crossing signal, a movable signal element mounted adjacent the crossing, vertically swinging depressible ramps associated with the railroad track and respectively disposed at opposite sides of the crossing adjacent to and remote from the latter, a drum mounted for rotation upon a vertical axis adjacent the free end of each ramp, operative connections between the free end of each ramp and the adjacent drum whereby said drum is caused to partially rotate in one direction upon depression of the ramp and in the other direction upon raising of said ramp, and operative connections between the drums and the signal elements including a flexible member having its ends anchored to and adapted to be wound upon said drums, said flexible member being elastic.

3. In a railroad crossing signal, a drum mounted for rotation upon a vertical axis, and provided with a peripheral obliquely disposed cam groove, a vertically swinging ramp hinged at one end to the outer side of a rail of the railroad track, and a member rigid with the free end of the ramp and projecting outwardly into the cam groove of the drum for effecting partial rotation of the latter upon vertical swinging movement of the ramp.

4. In a railroad crossing signal, a movable

signal element mounted adjacent the crossing, movable ramps associated with the railroad track and respectively disposed at opposite sides of the crossing adjacent to and remote from the latter, a drum mounted for rotation adjacent each ramp, operative connections between each ramp and the adjacent drum whereby said drum is caused to partially rotate in one direction upon movement of the ramp in one direction and to

partially rotate in the other direction upon movement of said ramp in the other direction, and operative connections between the drums and the signal elements including a flexible member having its ends anchored to and adapted to be wound upon said drums.

5. In a railroad crossing signal, a drum mounted for rotation and provided with a peripheral obliquely disposed cam groove, a movable ramp mounted adjacent a rail of the railroad track, and a member rigid with the ramp and projecting into the cam groove of the drum for effecting partial rotation of the latter upon movement of the ramp.

6. In a railroad crossing signal, an upright mounted at one side of the crossing, a transverse horizontal shaft journaled in the top of said upright and having a pulley and a vertically swinging signal arm fixed thereon, a further pulley journaled on the lower portion of said upright beneath the first named pulley, depressible ramps associated with the railroad track and respectively disposed at opposite sides of the crossing, and means including a flexible member connecting the ramps, said flexible member having a crossed intermediate portion trained about said pulleys, whereby the signal arm is actuated to lowered signaling position and one ramp raised when the other ramp is depressed and the signal arm is actuated to raised inoperative position and said other ramp raised when said one ramp is depressed.

7. In a railroad crossing signal, a vertically movable signal element mounted at the crossing, depressible ramps associated with the railroad track and respectively disposed at opposite sides of the crossing, and means operatively connecting the ramps and operatively connected to the signal element for actuating the latter to lowered signaling position and raising one ramp when the other ramp is depressed and for actuating the signal element to raised inoperative position and raising said other ramp when said one ramp is depressed.

In testimony whereof I affix my signature.
DAVID BROWN.
